UNITED STATES PATENT OFFICE

GIDEON RIETVELD, OF KNOXVILLE, IOWA

MATCH-BOX HOLDER

Application filed February 4, 1929. Serial No. 337,505.

The object of my invention is to provide a match box holder of simple, durable and inexpensive construction, which may be formed of sheet metal by the stamping process, and of few parts, and at the same time providing a match box holder which is adapted to receive the inner container of an ordinary match box, and to completely enclose and shield the match box container and its contents, and at the same time permits the matches to be easily removed.

More specifically it is the object of my invention to provide a match box holder adapted to receive and shield a box of matches supported therein, and to provide improved means whereby the matches may be easily and quickly removed.

A further object is to provide in a sheet metal box holder, having its bottom, top, sides and ends closed and one of its sides provided with an opening for delivering matches, improved means of simple construction for automatically closing said opening after the matches have been removed.

25 A further object is to provide in an enclosed match box holder, having an opening in one side for delivering matches, improved means for automatically feeding the matches to a position adjacent to said opening in a symmetrical manner whereby the matches may be easily and quickly removed.

30 My invention consists in the construction, arrangement and combination of the various parts of the device, whereby the objects contemplated are attained, as hereinafter more fully set forth, pointed out in my claims, and illustrated in the accompanying drawings, in which:

Figure 1 is a perspective view of my improved match box holder.

Figure 2 is a vertical sectional view of the same taken through the front and back showing the holder in its open position for receiving a match box.

45 Figure 3 is an end elevation of the upper end of the box in its closed position.

Figure 4 is an end elevation of the upper end of the holder in its open position.

50 Figure 5 is an enlarged, detail, sectional view taken on the line 5—5 of Figure 4.

Figure 6 is a detail sectional view taken on the line 6—6 of Figure 3.

Figure 7 is a detail, central sectional view of the lower end of the box in its closed position.

55

Figure 8 is a segmental perspective view of a portion of the front end of the holder with the door for closing the opening of the holder removed.

Figure 9 is a perspective view of the match box door.

Figure 10 is a blank of the main body portion of my improved match box holder.

The body of my improved match box holder is formed of a blank of sheet metal having the form illustrated in Figure 10, and comprises a rectangular body portion 10 having at one end a rectangular opening 11 and a depressed portion 12 at its opposite end. The side edges of the end portions of the body 10 is provided with flanges 13 and 14. The width of said flanges is slightly greater than half the depth of the finished holder. The length of said flanges is equal to the length of the finished holder. The inner ends of the members 13 and 14 are spaced apart a distance substantially equal to the depth of the holder, said inner edges being curved as illustrated. The side edges of the members 13 and 14, near their inner ends, are each provided with a substantially V-shaped notch 15. The distance between the apex of said notches and the side edges of the body portion 10 is equal to half the depth of the holder. The outer ends of each of the flanges 13 and 14 terminate inside 70 of the extreme ends of the body portion a distance somewhat greater than half the depth of the holder, to form bottom members 17. The inner ends of the members 13 and 14 are provided with a substantially V-shaped notch 15. The distance between the apex of said notches and the side edges of the body portion 10 is equal to half the depth of the holder. The outer ends of each of the flanges 13 and 14 terminate inside 75 of the extreme ends of the body portion a distance somewhat greater than half the depth of the holder, to form bottom members 17. The inner ends of the members 13 and 14 are provided with a substantially V-shaped notch 15. The distance between the apex of said notches and the side edges of the body portion 10 is equal to half the depth of the holder. The outer ends of each of the flanges 13 and 14 terminate inside 80 of the extreme ends of the body portion a distance somewhat greater than half the depth of the holder, to form bottom members 17. The inner ends of the members 13 and 14 are provided with a substantially V-shaped notch 15. The distance between the apex of said notches and the side edges of the body portion 10 is equal to half the depth of the holder. The outer ends of each of the flanges 13 and 14 terminate inside 85 of the extreme ends of the body portion a distance somewhat greater than half the depth of the holder, to form bottom members 17. The inner ends of the members 13 and 14 are provided with a substantially V-shaped notch 15. The distance between the apex of said notches and the side edges of the body portion 10 is equal to half the depth of the holder. The outer ends of each of the flanges 13 and 14 terminate inside 90 of the extreme ends of the body portion a distance somewhat greater than half the depth of the holder, to form bottom members 17. The inner ends of the members 13 and 14 are provided with a substantially V-shaped notch 15. The distance between the apex of said notches and the side edges of the body portion 10 is equal to half the depth of the holder. The outer ends of each of the flanges 13 and 14 terminate inside 95 of the extreme ends of the body portion a distance somewhat greater than half the depth of the holder, to form bottom members 17. The inner ends of the members 13 and 14 are provided with a substantially V-shaped notch 15. The distance between the apex of said notches and the side edges of the body portion 10 is equal to half the depth of the holder. The outer ends of each of the flanges 13 and 14 terminate inside 100 of the extreme ends of the body portion a distance somewhat greater than half the depth of the holder, to form bottom members 17.

The flanges 13 and 14 are bent along the dotted lines 16 to position at right angles to said body portion, both sets of flanges being bent in the same direction. The bottom members 17 are then bent on the dotted lines 18 in the same direction as the flanges 13 and 14.

The upper end of the body member, as illustrated in Figure 10, is bent along the dotted lines 19, while the bottom of the body portion is bent along the dotted lines 20, so that the upper portion of the body 10 forms the

back 21 of the holder, while the lower portion forms the front 22.

The back and front members are bent to position where they are substantially parallel with the side edges of the corresponding members 13 and 14 overlapping with one of the notches 15 of the corresponding side members entering the other notch, so that the side edges of the members 13 and 14 overlap. The overlapping portions are offset in the manner illustrated in Figure 6.

By this arrangement it will be seen that a lug 23, formed by the notch 15 of one of the flange members, will be supported inside of the corresponding lug 24, while an overlapping side member 25 will rest outside of an underlapping side member 26, in the manner shown in Figure 2.

Thus it will be seen that means is provided for locking the upper ends of the flanges 13 and 14 together. The said flanges form the side members of the completed holder. The holder is made somewhat resilient so that it naturally assumes the position illustrated in Figure 2.

The free ends of the two halves of the holder are separated such a distance as to permit a match box to be placed between them and inserted into the back half of the holder in an upright position, in the manner illustrated by dotted lines in Figure 2, with the front of the match box open. The front half is then swung inwardly with the end members 17 having the opening 11 underlapping the member having the depression 12, so that the said depression enters the opening 11 and forms means for locking the two halves of the holder together, in the manner illustrated in Figure 7.

It will be seen that as one set of the V-shaped notches 15 enters the corresponding notches, as the two halves of the holder are moved to a closed position, the coacting bottom edges of said notches will form a sort or fulcrum with the portions of the holder member below said notches moving inwardly toward each other as the holder is moved to a closed position, and the portions of the members above said notches will be simultaneously moved outwardly from each other, in such a manner that the points of intersection between the top member 19 and the front and back members will be stretched and caused to be straightened out and snugly engage the curved upper ends of the flanges 13 and 14, so that a comparatively tight fit may be maintained between said upper curved end portions and the top member 19.

The straightening out and stretching of the top member 19 provides means for assisting in throwing the lower ends of the halves of the holder apart when the bottom members 17 are released by pressing the member 12 inwardly, it being understood that the bottom members 17 and the member

12 are formed of yieldable and resilient material. The resiliency of the top member 19 also assists in separating the lower ends of the two halves.

The back 21 is provided with a small opening 27 having a slot 28 for receiving a nail 29, or other suitable means for supporting the box. A similar but larger opening 31 is provided near the bottom end of the back 21, which may also be provided with a suitable supporting pin or nail if so desired. The larger opening 30 also provides means whereby the match box may be removed from the holder by inserting the operator's finger.

The front member 22 is provided with a substantially U-shaped slot 31, having at its free ends laterally extending portions 32 to form a guide plate 33, bent inwardly and downwardly in the manner illustrated in Figures 2 and 8, and forms an opening 34 through which the matches may be removed. The inner end of the guide 33 is curved downwardly and adapted to project into the match box a slight distance, so that matches will be fed to the lower end of the holder in a symmetrical manner and in parallel relation with each other and with the bottom of the holder. A portion of the matches in the top portion of the match box, when it is full, rest on the guide plate 33.

The guide plate 33 provides means whereby a recess 35 may be provided through which the matches may be easily removed, and also in which a suitable door may be swung for closing the opening 34.

The door which I have provided for closing said opening is formed of a single piece of sheet metal, comprising a body portion 36 having its upper edge bent outwardly and then upwardly to form a flange 37. The width of the door 36 is equal to the distance between the notches 32 and designed to be slid into said notches with the flange 37 resting against the shoulders formed by the notches 32, so that said shoulders and the flange 37 act as a hinge for the door 36. The central portion of the door 36 is provided with an inverted, substantially U-shaped slot 38 to form a tongue 39, the free end of which is bent inwardly and designed to rest against the upper end of the guide plate 33, in the manner shown in Figure 2. The tongue 39 acts as a spring by means of which the door 36 is automatically moved to a closed position. The door 36 is slightly larger than the opening 34 so that its edges rest inside of and adjacent to the front member 22.

The upper corners of the underlapping members 13 are bent inwardly at 40, as shown in Figure 6, to permit the holder to be easily folded together, so that said underlapping portions will always be supported inside of the outer overlapping portions,

thereby preventing the overlapping portions from accidentally being moved to improper relation with each other.

Thus it will be seen that I have provided a match box holder, the main body of which is constructed of a single piece of sheet metal, having the form of two halves with their inner edges arranged in telescopic relation and their upper ends pivotally connected, so that their lower ends are free to move from each other, to permit a match box to be inserted, after which the free ends are moved together and latched, forming a comparatively tight holder. The holder is provided with a suitable door which is also formed of a single piece of sheet metal operatively mounted in position without hinges or other pivoting devices, and yieldably supported to automatically assume a closed position without the use of extra mechanism such as springs, any other than the resiliency of the metal of which the holder is constructed. The halves of the holder are locked in their closed position by an efficient locking device, which is formed of the bottom members of the holder. The holder is so constructed that when a match box is placed therein, matches will not be accidentally thrown out, and which is substantially fireproof in case the matches within should become ignited, and at the same time the matches may be easily and quickly removed.

I claim as my invention:

1. A match box holder comprising a section having a back, sides and a bottom member, and another section having a front, sides and a bottom member, the open sides of said sections being adjacent and provided with a common resilient top member, the free edges of said side members being provided with coacting notches to form fulcrums, whereby the two sections may be pivotally mounted together, and means for latching said members in a closed position.

2. A match box holder comprising a section having a back, sides and a bottom member, and another section having a front, sides and a bottom member, the open sides of said sections being adjacent and provided with a common resilient top member, the free edges of said side members being provided with coacting notches to form fulcrums, whereby the two sections may be pivotally mounted together, and to provide means for stretching the top member adjacent to the top ends of said sides as the free ends of said sections are moved together, and means for latching said free ends in a closed position.

3. A match box holder comprising a section having a back, sides and a bottom member, and another section having a front, sides and a bottom member, the upper ends of said side members being curved, and the

open ends of said sections being mounted adjacent and provided with a common resilient top member, the free edges of said side members having coacting notches to form fulcrums, whereby the two sections may be pivotally mounted together, and to provide means for stretching the top member adjacent to the curved ends of said side members as the free end of said sections are moved to closed position, and means for latching said free ends together.

4. A match box holder comprising a section having a back, sides and a bottom member, and another section having a front, sides and a bottom member, the open sides of said sections being adjacent and provided with a common resilient top member, the free edges of said side members being provided with coacting notches to form fulcrums, whereby the two sections may be pivotally mounted together, the free edges of said bottom members overlapping, one of said overlapping portions including an opening and the other a depression for entering said opening and for latching said sections together.

5. A match box holder having a front provided with a substantially U-shaped slot to form a tongue, having its free end bent inwardly and downwardly to form a guard plate, a delivery opening in said front, the upper ends of said slots having outwardly projecting notches, and a door formed of a single piece of sheet metal having an outwardly extending flange at its upper end and mounted in the outwardly projecting notches of said slots.

6. A match box holder having a front provided with a substantially U-shaped slot to form a tongue, having its free end bent inwardly and downwardly to form a guard plate, a delivery opening in said front, the upper ends of said slots having outwardly projecting notches, and a door formed of a single piece of sheet metal having an outwardly extending flange at its upper end and mounted in the outwardly projecting notches of said slots, the center of said door being provided with a substantially inverted U-shaped notch to provide an inwardly and upwardly projecting tongue having its free end designed to engage the inwardly and downwardly projecting shield plate, the last said tongue providing yieldable means for closing said door.

7. A match box holder comprising a section having a back, sides and a bottom member, and another section having a front, sides and a bottom member, the open sides of said sections being adjacent and provided with a common resilient top member, the free edges of said side members being provided with coacting notches to form fulcrums whereby the two sections may be pivotally mounted together, and means for latching the free

ends of said sections together, said front member being provided with a substantially U-shaped notch to form an inwardly and downwardly projecting tongue, and a delivery opening in said front.

5. A match box holder comprising a section having a back, sides and a bottom member, and another section having a front sides and a bottom member, the open sides of said sections being adjacent and provided with a common resilient top member, the free edges of said side members being provided with coacting notches to form fulcrums whereby the two sections may be pivotally mounted together, means for latching the free ends of said sections together, said front member being provided with a substantially U-shaped notch to form an inwardly and downwardly projecting tongue, a delivery opening in said front, a pivotally mounted door for said opening, and yieldable means for closing said door.

10. A match box holder comprising a section having a back, sides and a bottom member, and another section having a front, sides and a bottom member, the open sides of said sections being adjacent and provided with a common resilient top member, the free edges of said side members being provided with coacting notches to form fulcrums whereby the two sections may be pivotally mounted together, means for latching the free ends of said sections together, said front member being provided with a substantially U-shaped notch to form an inwardly and downwardly projecting tongue, a delivery opening in said front, the free ends of said U-shaped slot being provided with outwardly projecting notches, and a door formed of a single piece 25 of sheet metal supported in said notches and having an outwardly projecting flange at its upper end to limit the downward movement of said door, the said door having an inverted substantially U-shaped slot to form an inwardly projecting tongue, the free end of which is designed to rest against the inwardly projecting tongue of said front member.
